UNITED STATES PATENT OFFICE.

AUGUSTUS F. HARTER, OF CHICAGO, ILLINOIS, ASSIGNOR TO CRIBBEN & SEXTON COMPANY, OF CHICAGO, ILLINOIS, A CORPORATION OF ILLINOIS.

DESIGN FOR A COOKING-STOVE.

SPECIFICATION forming part of Design No. 36,321, dated May 12, 1903.

Application filed April 10, 1903. Serial No. 152,083. Term of patent 7 years.

To all whom it may concern:

Be it known that I, AUGUSTUS F. HARTER, a citizen of the United States, residing at Chicago, in the county of Cook and State of Illinois, have invented a new, original, and ornamental Design for Cooking-Stoves, of which the following is a specification, reference being had to the accompanying drawing, forming part thereof.

10 The figure is a perspective view of a cooking-stove, showing my new design.

As shown in the drawing, my design consists in providing on the outer surface of the legs raised and depressed portions, imparting 15 the appearance thereto shown in the drawing, and in providing on the downwardly-extending flange extending around the stove and uniting the legs a series of scrolls. The vertical exterior surface of the stove below 20 the horizontal cooking-surface is ornamented by raised and depressed portions arranged in

the manner shown in the drawing. The front surface of the vertical back of the stove which rises above the horizontal cooking-surface is ornamented to correspond in character to the ornamentation on the vertical surface below the horizontal cooking-surface. Above the shaft at the top of the vertical back portion of the stove is a casting ornamented as shown. 25

Having described my invention, what I claim as new, and desire to secure by Letters Patent, is—

The ornamental design for a cooking-stove, 30 as herein shown and described.

In witness whereof I have hereunto subscribed my name in the presence of two subscribing witnesses.

AUGUSTUS F. HARTER.

In presence of—

PETER BAUM,
W. A. SMITH.
